INVENTOR.

UNITED STATES PATENT OFFICE

153,326

DESIGN FOR A FLUORESCENT LAMP OR SIMILAR ARTICLE

Carl Edward Swanson, Chicago, Ill.

Application May 17, 1946, Serial No. 129,778

Term of patent 14 years

(Cl. D48—20)

To all whom it may concern:

Be it known that I, Carl Edward Swanson, a citizen of the United States, and residing in the city of Chicago, in the county of Cook and State of Illinois, have invented a new, original, and ornamental Design for Fluorescent Lamp or Similar Article, of which the following is the specification, reference being had to the accompanying drawings, which form a part thereof.

On the drawings:

Fig. 1 is an elevational view of a fluorescent lamp or similar article, showing my new design.

Fig. 2 is a top plan view thereof.

I claim:

The ornamental design for a fluorescent lamp or similar article, as shown.

CARL EDWARD SWANSON.
